(57) **CLAIM**

The ornamental design for a bracket assembly, as shown and described.

DESCRIPTION

FIG. 1 is a front view of a bracket assembly in accordance with the present design;

FIG. 2 is a rear view of the bracket assembly of FIG. 1;
FIG. 3 is a left side view of the bracket assembly of FIG. 1;
FIG. 4 is a right side view of the bracket assembly of FIG. 1;

FIG. 5 is a top view of the bracket assembly of FIG. 1;
FIG. 6 is a bottom view of the bracket assembly of FIG. 1;
and,
FIG. 7 is a perspective view of the bracket assembly of FIG. 1.

The broken lines shown in the drawings represent portions of the bracket assembly that form no part of the claimed design.
